PROCESS FOR PREPARING ALKALINE METALS
HAVING HIGH REACTIVE POWER

Werner Muench, Cesano Maderno, and Luigi Notarbartolo and Giuliana Silvestri, Milan, and Vincenzo Ruoti, Cesano Maderno, Italy, assignors, by mesne assignments, to Snia Viscosa Societa Nazionale Industria Applicazioni Viscosa S.p.A., Milan, Italy, a company of Italy

Claims priority, application Italy Mar. 23, 1956

7 Claims. (Cl. 260—665)

It is known that some hydrocarbons add finely distributed alkaline metals (Schlenk, Ber., 47, 473 (1914)). These hydrocarbons possess conjugated double bonds activated by aromatic groups which may be either simple or conjugated. It is also known that these hydrocarbons can add normally two metal atoms, by giving up one of those activated double bonds and in exceptional cases even only one single metal atom. In most cases these additions of metals are effected in ether or in a cyclic ether in the absence of water and of the oxygen of air.

It has now been found and this represents the object of the present invention, that these hydrocarbons are able to add not only two atoms of metal, as is indicated in the literature, but, under suitable operating conditions, a sensibly greater number of metal atoms per molecule of non-saturated hydrocarbon.

In many cases this alkali-metal linked in excess gives the same reactions that are caused by the free alkali-metal.

It is not possible to define accurately the manner in which the quite considerable quantities of alkaline metal are linked by those hydrocarbons. It may be that the addition takes place by means of a progressive dissolving of all the double links, that is, also of those of the aromatic series. However, it may also be that there is only a solid solution of the alkaline metal at the surface of the hydrocarbon.

If those hydrocarbons containing more than two molecules of alkaline metal per molecule of addition compound, are decomposed with alcohol or water, a quantity of hydrogen is obtained which in most cases corresponds approximately to the quantity of x minus 2, where x represents the quantity in molecules of alkaline metal that is absorbed by the hydrocarbon. If then for instance six molecules of sodium are absorbed by one molecule of anthracene and the compound formed is decomposed with water, there is obtained a quantity of hydrogen that corresponds about to four molecules of sodium.

What has been set forth hereinbefore is true with the approximative accuracy only in the case in which the first two molecules of sodium are absorbed while in mutual position 1,4, as happens with anthracene. If the first two molecules of alkaline metal have been added in position 1,2 during the decomposition there is obtained a quantity of hydrogen slightly greater than would correspond to the formula $x-2$.

The production of these addition compounds of alkaline metals is extraordinarily simple. It is only necessary to treat with the alkaline metal a suitable hydrocarbon in an inert solvent or in a suspending medium such as toluene, xylene, paraffin oil etc., preferably at elevated temperature and excluding water and the oxygen of air.

It is advantageous but not necessary to effect this treatment in such a manner that the hydrocarbon be treated with the alkaline metal at first for the duration of one or

2

more hours in the cold and keeping then the temperature further for from one to three hours above the melting point of the alkaline metal. It may even be advantageous to add at the beginning a small quantity of a metal-organic addition compound previously prepared.

The comparatively elevated temperature indicated above is not indispensable; however, it is possible therewith to reduce the duration of the reaction. If operating at temperatures beyond the melting point of the alkaline metal, it is not always necessary to employ the alkaline metal finely distributed. It is possible to employ even pieces of any size.

So it is not always necessary to add the whole quantity of alkaline metal that one wants to add to the hydrocarbon, at once at the beginning, although this be the preferred method of production. Above all if it is desired to carry out this reaction for the first time with a new hydrocarbon it may be advisable to use first only 2 molecules of alkaline metal per molecule of desired addition compound and to add further alkaline metal after those molecules having been absorbed completely.

These addition compounds appear as heavy colored powders, mostly of black bluish color or black towards brown color, which separate from the solvent or from the suspension medium in the shape of a fine sand.

Hydrocarbons suitable are for instance anthracene, phenanthrene, stilbene, diphenyl butadiene, fulvene and others.

The alkaline-organic addition compounds containing more than two molecules of metal per molecule of hydrocarbon, can be employed in lieu of the alkaline metal, for instance as reducing agents in organic chemistry or in the polymerization of butadiene catalyzed by means of alkali metal. These sodium compounds and processes of making them and uses as activators of catalysts are described but not claimed in our copending applications Serial Nos. 646,552 and 646,554 filed March 18, 1957.

Example 1

- 40 To 170 g. of anhydrous xylene in a nitrogen atmosphere there are added 25.8 g. of sodium finely comminuted, and 20 g. of anthracene. The mixture is stirred at first for two hours at ordinary temperature and then from 0.1 to 0.2 g. of di-sodium anthracene are added. The mixture is slowly heated to 100° C., its color becomes intensive blue already in the cold or as soon as the temperature begins to rise. The sodium which at the beginning is perfectly visible, slowly disappears completely and after three hours the reaction is terminated and after stopping the stirrer the deca-sodium anthracene 50 deposits as a sandy powder of bluish-black color under the clear and colorless liquid. For the analysis, about 0.5 to 1.5 ml. are put into a small flask without exposing to contact with air. Accurate weighing is useless because the quantity of sodium obtained during the experiment is determined afterwards by titration with $n/10$ H_2SO_4 . The flask is closed with a double-bored rubber stopper. One of the bores serves to connect the small flask with a buret filled with water, the other one for connecting with the upper part of a Bunte buret filled 55 with water the lower part of which is connected with a level vessel. From the buret about 5 ml. of water are allowed to pass into the small flask, the latter is agitated, the hydrogen developed is brought into the Bunte buret by lowering the level vessel, this operation is repeated if 60 needed until no more hydrogen is found to develop and finally the flask is filled completely with water. Then the Bunte buret is closed and as usual the volume of gas obtained is determined, from which the cubit centimetres of water are deducted which have been employed 65 for the decomposition of the sodium compound and for filling the flask. Now the procedure of usual titration 70 for the decomposition of the sodium compound and for filling the flask.

is followed with $n/10$ sulfuric acid, of the content of the flask. On the basis of the titration the overall quantity of sodium is calculated.

Result of the analysis:

(I) Hydrogen developed by means of decomposition and collected above water, reduced to normal pressure and to 0°C :

(a_1) 44.87 cu. cm.

(a_2) 42.38 cu. cm.

(II) Titration with $n/10$ sulfuric acid:

(b_1) 52.00 cu. cm. of $n/10\text{ H}_2\text{SO}_4$ =58.30 cu. cm. of H_2 .

(b_2) 49.65 cu. cm. of $n/10\text{ H}_2\text{SO}_4$ =55.66 cu. cm. of H_2 .

Hence the ratio $b_1:a_1$ is equal to 1:0.78 or 10 mol:7.8 mol.

The ratio $b_2:a_2$ is therefore equal to 1:0.77 or 10 mol:7.7 mol.

This corresponds for both analyses with good approximation to the value of 10 moles to 8 moles.

Example 2

Into 150 g. of paraffin oil free from water and in a nitrogen atmosphere there are introduced 10.3 g. of comminuted sodium and 19.9 g. of anthracene. The mixture is stirred for four hours at normal temperature, 0.1 g. of tetra-sodium anthracene is added and the mass is heated for three hours up to 110°C . In most cases already in the cold or at the beginning of heating, the suspension becomes dark-colored. After stopping the stirrer, the tetra-sodium anthracene formed separates from the clear and colorless liquid. The analysis (carried out as described in Example 1) give the following data:

(I) Hydrogen developed by means of decomposition and collected above water, reduced to normal pressure and at 0°C :

(a_1) 4.46 cu. cm.

(a_2) 6.25 cu. cm.

(II) Titration with $n/10$ sulfuric acid:

(b_1) 9.15 cu. cm. of $n/10\text{ H}_2\text{SO}_4$ =10.25 cu. cm. of H_2 .

(b_2) 10.05 cu. cm. of $n/10\text{ H}_2\text{SO}_4$ =12.4 cu. cm. of H_2 .

The ratio $b:a$ are equal to 1:0.44 and 1:0.5 respectively, which corresponds approximately to the ratio of 4 molecules to 2 molecules.

Example 3

To 200 g. of anhydrous xylene in nitrogen atmosphere there are added 15.2 g. of finely comminuted sodium and 20 g. of stilbene. The mixture is stirred for 12 hours at normal temperature and in nitrogen atmosphere, 0.1 to 0.2 g. of di-sodium stilbene are added and under stirring the mass is heated for 8 hours to 100°C . The suspension becomes dark-colored at once and after stopping the stirrer the hexa-sodium stilbene separates in the shape of a brown-black colored powder. The analysis of two samples of the substance, carried out as described in Example 1, give the following values:

(I) Hydrogen developed by means of decomposition and collected above water, reduced to normal conditions:

(a_1) 14.84 cu. cm.

(a_2) 22.4 cu. cm.

(II) Titration with $n/10\text{ H}_2\text{SO}_4$:

(b_1) 17.55 cu. cm. of $n/10\text{ H}_2\text{SO}_4$ =19.66 cu. cm. of H_2 .

(b_2) 25.9 cu. cm. of $n/10\text{ H}_2\text{SO}_4$ =29.0 cu. cm. of H_2 .

The ratio $b_1:a_1$ is equal to 1:0.77 and the ratio $b_2:a_2$ is equal to 1:0.75; this corresponds to a molecular ratio of 6:4.5.

Example 4

To 150 g. of anhydrous xylene in nitrogen atmosphere there are added 7 g. of comminuted sodium and 18.05 of anthracene. The mixture is treated as described in the preceding examples and a product is obtained the analytical values whereof, as indicated here below, correspond about to those of tri-sodium anthracene. During some experiments however it is found that the anthracene added has not reacted completely. If allowing to rest, sometimes there deposits under the clear liquid also some non-transformed anthracene. It may be that a tri-sodium anthracene itself does not exist and that a mixture is obtained of disodium anthracene with other sodium anthracenes which contain more than two atoms of sodium, such as for instance tetra-sodium or hexa-sodium anthracene. It is also possible that during certain experiments made for the production of di-sodium anthracene there are obtained compounds containing more than two atoms of sodium, besides the anthracene not transformed. The analysis of the substance obtained during the experiment described hereinbefore has given the following results:

(I) Hydrogen obtained by means of decomposition with water, reduced to normal conditions:

(a_1) 7.1 cu. cm.

(a_2) 9.8 cu. cm.

(II) Titration with $n/10\text{ H}_2\text{SO}_4$:

(b_1) 22.63 cu. cm. of $n/10\text{ H}_2\text{SO}_4$ =25.3 cu. cm. of H_2 .

(b_2) 29.47 cu. cm. of $n/10\text{ H}_2\text{SO}_4$ =33.0 cu. cm. of H_2 .

The ratio of $b:a$ are 3.56:1 and 3.33:1, which corresponds approximately to the ratio of 3 molecules to 1 molecule.

We claim:

1. A process of forming an alkali-metal compound of a normally solid polynuclear aromatic hydrocarbon containing 2-10 atoms alkali-metal comprising stirring an alkali-metal with said aromatic hydrocarbon for at least about two hours in an inert anhydrous liquid hydrocarbon at atmospheric temperature under a non-oxidizing atmosphere and then heating to about 100°C . to about 110°C . with stirring until a dark precipitate forms.

2. A process according to claim 1, wherein the aromatic compound is anthracene.

3. A process according to claim 1, wherein the aromatic compound is stilbene.

4. A process according to claim 1, wherein the aromatic compound is phenanthrene.

5. A process according to claim 1, wherein the aromatic compound is diphenyl butadine.

6. A process according to claim 1, wherein the liquid hydrocarbon is a benzene homologue.

7. A process according to claim 1, wherein the liquid hydrocarbon is paraffin oil.
